(57) **CLAIM**

The ornamental design for a vanity mirror, as shown and
described herein.

DESCRIPTION

FIG. 1 is a top, front, left-side perspective view of a vanity
mirror embodying our design;

FIG. 2 is a front elevation view thereof;

FIG. 3 is a right-side elevation view thereof;

FIG. 4 is a left-side elevation view thereof;

FIG. 5 is a top plan view thereof;

FIG. 6 is a bottom plan view thereof; and,

FIG. 7 is a rear elevation view thereof.

The dash-dash broken lines shown in the drawings represent
portions of the vanity mirror that form no part of the claimed
design. The dash-dot-dash broken lines shown in the draw-
ings represent the boundaries of what is claimed and form no
part of the claimed design.
